PUMP

Joseph A. Tennant, Houston, Tex., assignor, by
mesne assignments, to Stephens Pump Com-
pany, Round Rock, Tex., a corporation of
Delaware

Application May 14, 1934, Serial No. 725,568

8 Claims. (Cl. 103—44)

This invention relates generally to pumps.

It will be found particularly useful in pumps designed for pumping abrasive and corrosive fluid of the general type disclosed by Letters Patent 5 of the United States to Stephens No. 1,848,441 of March 8, 1932. A conventional pump of this type adapted for use as a mud or slush pump in deep well drilling includes a barrel; inlet and outlet valves therefor; a hollow expandable member 10 within the barrel; and a reciprocable piston to actuate pumping fluid confined within the expandable member to cause expansion and contraction thereof whereby pumped fluid is drawn into and forced out of said barrel.

In pumps of other types the pumped fluid is in contact with the piston and rod and carries away the heat generated by the reciprocation of the piston and rod through conventional packings. In the type of pump to which this invention 15 relates, however, the piston and rod are sealed off from the fluid being pumped and the heat so generated is therefore transferred to the pumping fluid within the expandable member. These expandable members are usually made of rubber, 20 which is a very good heat insulator, and the pumping fluid within the expandable member is in contact with very little metal. Under certain conditions, such as when the packings are inadvertently made too tight, the heat is not dissipated 25 as rapidly as it is generated. And so, under such conditions, the pumping fluid in the expandable member will reach a very high temperature whereby the expandable member will be injured; and when the pressure on the pumping fluid is 30 reduced on the suction stroke of the piston, the pumping fluid will boil so that the pumping member will remain expanded, which renders the pump inoperative.

This invention has for its general object the 35 provision of new and improved means to prevent heating of the pumping fluid to an objectionably high temperature by cooling the packing to remove the heat where it is generated and before it enters the pumping fluid in the expandable member.

A specific object of the invention is to provide means to so cool the packing with the pumped fluid as a coolant.

Another specific object is to so cool the packing 40 by circulating therethru a coolant from an external source independently of the pump.

Other objects will hereinafter appear.

The preferred embodiment of the invention is 45 illustrated by the accompanying drawing which 50 is a sectional elevation of one of the barrels of

the pump equipped with the packing cooling means.

As the operation of this pump is clearly set forth in the said patent to Stephens No. 1,848,441, it will be but briefly referred to here as follows:

In the drawing the barrel is indicated at 1, and the inlet and outlet means at 2 and 3, the latter including valves not shown. Within the barrel 1 is a hollow expandable member 4 which may comprise a rubber sleeve having an external annular flange 5 secured to one end wall of the barrel 1 by the ring 6; and an external annular flange 7 secured to the other end wall of the barrel by a ring 8. The numeral 9 indicates the piston which is reciprocated by means not shown to actuate the pumping fluid within the expandable member 4 10 to draw the pumped fluid into the barrel 1 through the inlet means 2, and to expel it from the barrel 1 through the outlet means 3. When the piston 9 is at the end of its suction stroke as shown, the shape of the expandable member 4 is substantially 15 cylindrical, and the barrel 1 is filled with pumped fluid. When the piston 9 moves to the right on its discharge stroke it displaces the pumping fluid in said expandable member and causes said expandable member to expand. During such expansion the inlet valve (not shown) of the means 2 remains closed and the outlet valve (not shown) of the means 3 opens to permit the pumped fluid 20 to be expelled from the barrel 1 through the outlet means 3. Now when the piston moves to the left on its suction stroke the expandable member 4 contracts from its expanded shape into its contracted shape; and as the valve (not shown) of the outlet means 3 then remains closed, and the valve (not shown) of the inlet means 2 opens, a 25 fresh charge of pumped fluid is thereby drawn into the barrel 1. It will be obvious that as the piston 9 reciprocates the pumped fluid will be alternately drawn into and expelled from the 30 barrel.

The means whereby the ends of the expandable member 4 are sealed to the barrel 1 may, of course, be varied without departing from the present invention. The construction herein disclosed for that purpose will form the subject matter of another application.

Referring now to the new and improved means provided by this invention for the purposes above set forth, it will be noted that the packing 10 is 45 surrounded by a packing cooler 11 which includes an annular longitudinally elongated passageway 12. The cooler 11 is secured to the barrel 1 by suitable bolts not shown, and it in turn holds the ring 8 against the flange 7 of the expandable 50 55

member 4, the packing 10 being held in place by the gland 13 and ring nut 14.

The annular passageway 12 of the cooler is connected by the pipes 15 and 16 to the inlet 5 passageway 17 leading to the inlet means 2, and by the pipes 18 and 19 to the outlet passageway 20 leading from the outlet means 3. The said passageway 12 of the cooler is also connected by the pipes 18 and 21 and 15 and 22 to an external 10 coolant source of supply, a pump indicated at 23 being disposed in the pipe 21 to cause the coolant to circulate through the cooler passageway 12. The valves 24, 25, 26 and 27 are provided so that the pumped fluid and the coolant from the external 15 source of supply may, if desired, be alternately supplied to the passageway 12 to keep the packing 10 cool in a manner which will now be described.

If the valves 24 and 26 are closed and the valves 20 25 and 27 open, when the piston 9 is reciprocated a portion of the pumped fluid being discharged through the outlet 20 will pass through the pipes 19 and 18 and through the annular passageway 12 of the cooler to prevent the excessive generation 25 of heat, and thence through the pipes 15 and 16 into the inlet 17.

If the valves 25 and 27 are closed and the valves 24 and 26 open, and the coolant pump 23 operated, the coolant may be forced from the external 30 source of supply through the pipes 21 and 18 into the annular passageway 12 of the cooler to prevent the generation of excessive heat, and thence through pipes 15 and 22 back to the source of coolant supply.

35 It will be apparent in view of the foregoing that the heat is removed before it enters the pumping fluid in the expandible member 4; that is, it is removed from the packing and piston by which it is generated.

40 The invention is not limited to the preferred embodiment herein disclosed. Various changes will occur to those skilled in the art, and may be made within the scope of the following claims.

I claim:

45 1. A pump having a barrel; inlet and outlet means for said barrel; a hollow expandible pumping member supported by and sealed in said barrel; pumping fluid in said member; a packing; a piston extending through and reciprocable in 50 said packing to actuate said pumping fluid to effect the expansion and contraction of said member to draw pumped fluid into said barrel through said inlet means, and to expel it from said barrel through said outlet means; a cooler 55 surrounding said packing and communicating with said inlet means and outlet means so that a portion of the pumped fluid discharged through said outlet means will pass through said cooler into said inlet means, said cooler being shut off 60 from fluid communication with said pumping fluid.

2. A pump having a barrel; inlet and outlet means for said barrel; a hollow expandible pumping member supported by and sealed in said 65 barrel; pumping fluid in said member; a packing; a piston extending through and reciprocable in said packing to actuate said pumping fluid to effect the expansion and contraction of said member to draw pumped fluid into said barrel through said inlet means, and to expel it from said barrel through said 70 outlet means; a hollow annulus having a central opening for the reception of the piston and being closed against fluid communication with said pumping fluid, and a counterbore for said packing arranged to seal one end of said pump barrel, said annulus having a peripheral flange for 75 securing to the barrel to seal the expandible member therein; a packing gland and ring sealing the packing to the piston and secured to said annulus; and means connecting the pump outlet

being shut off from fluid communication with said pumping fluid.

3. A pump having a barrel; inlet and outlet means for said barrel; a hollow expandible pumping member supported by and sealed in said 5 barrel; pumping fluid in said member; a packing; a piston extending through and reciprocable in said packing to actuate said pumping fluid to effect the expansion and contraction of said member to draw pumped fluid into said barrel through 10 said inlet means, and to expel it from said barrel through said outlet means; a packing cooler extending along said packing and communicating with said outlet means so that a portion of the pumped fluid discharged through said outlet 15 means will pass through said cooler, said cooler being shut off from fluid communication with said pumping fluid.

4. A pump having a barrel; a hollow expandible pumping member supported by and sealed in 20 said barrel; pumping fluid in said member; a packing; a piston extending through and reciprocable in said packing to actuate said pumping fluid to effect the movement of pumped fluid thru said barrel; a packing cooler extending along 25 said packing and being closed against passage of cooling fluid into said pumping fluid; and means to convey to said packing cooler pumped fluid discharged from said barrel.

5. A pump having a barrel, inlet and outlet 30 means for said barrel; a hollow expandible pumping member supported by and sealed in said barrel; pumping fluid in said member; a packing; a piston extending through and reciprocable in 35 said packing to effect the expansion and contraction of said member to draw pumped fluid into said barrel through said inlet means, and to discharge it from said barrel through said outlet means; a cooler surrounding said packing and closed against passage of cooling fluid into said 40 pumping fluid; and means to circulate a cooling fluid through said cooler.

6. A pump having a barrel; inlet and outlet means for said barrel; a hollow expandible pumping member supported by and sealed in said barrel; pumping fluid in said member; a packing; a piston extending through and reciprocable in 50 said packing to effect the expansion and contraction of said member to draw pumped fluid into said barrel through said inlet means, and to discharge it from said barrel through said outlet means; a packing cooler extending along said 55 packing and closed against communication with said pumping fluid; and means to circulate a cooling fluid through said cooler, independently 60 of said pump.

7. A pump having a barrel; inlet and outlet means for said barrel; a hollow expandible pumping member sealed in said barrel; pumping fluid in said member; a packing; a piston extending 65 through and reciprocable in said packing to actuate said pumping fluid to effect the expansion and contraction of said member to draw pumped fluid into said barrel through said inlet means, and to expel it from said barrel through said outlet means; a hollow annulus having a central opening for the reception of the piston and being closed against fluid communication with said pumping fluid, and a counterbore for said packing arranged to seal one end of said pump barrel, said annulus having a peripheral flange for 70 securing to the barrel to seal the expandible member therein; a packing gland and ring sealing the packing to the piston and secured to said annulus; and means connecting the pump outlet

to the hollow portion of said annulus whereby to cool the packing by the passage of the discharged pumped fluid.

8. A pump having a barrel, a hollow expandible pumping member supported by and sealed in said barrel, pumping fluid in said member, a packing, a piston extending through and recip-

rocable in said packing to actuate said pumping fluid to effect the movement of the pumped fluid through said barrel, and means for passing a portion of the pumped fluid about said packing, said means being closed against fluid communication with said pumping fluid. 5
